OF NEWTON, MASSACHUSETTS.

TENSION MECHANISM.

Application filed February 26, 1927. Serial No. 171,348.

This invention relates to tensioning devices for use on wrapping machines, especially, although not exclusively, wrapping machines wherein a roll of wrapping material is rotatably mounted upon a shuttle which, in turn, is adapted to rotate around the article being wrapped, such as a tire.

The invention contemplates the provision of an improved tensioning device adapted to exert a braking action preventing the free rotation of the roll of wrapping material by a brake mechanism mounted for engagement with the rotatable reel or spool carrying the roll of wrapping material, said tensioning device being of the type wherein the braking force is automatically proportioned to the diameter of the roll, being of simple but effective construction, and being so disposed upon the shuttle as to minimize the action of centrifugal force due to the rotation of the shuttle when employed in connection with shuttles of the rotary type.

The foregoing and other objects of the invention will be more clearly understood from the following description in conjunction with the accompanying drawings, in which,

Fig. 1 is an elevational view of a wrapping machine in which the invention is embodied;

Fig. 2 is a detail elevational view of the tension device constructed in accordance with the principles of the invention; and

Fig. 3 is a detail plan view of the same.

The machine shown in the drawings for the purpose of illustration comprises a base 10 carrying uprights 11 in which rollers 12 are suitably mounted for rotation and are arranged to be driven by any suitable driving mechanism, generally indicated at 33, to rotate the article or work W which is to be wrapped. The article is appropriately held in contact with the rollers 12 by a roller 13 rotatably mounted upon a weighted arm 14 pivotally secured to a post 15 mounted upon the base 10. A shuttle 16 provided with a tongue 17 is held for rotation between a plurality of rollers 18, having grooves 19, rotatably mounted upon the yoke 21 pivotally mounted to turn about a shaft 22 in a support 23 extending upwardly from the base 10. The yoke 21 is adjustably secured in a post 25 on the base 10 by a clamp 26. The shuttle 16 may be rotated around the article to be wrapped in any appropriate manner

such as by a friction disc 31 secured to the shaft 22 and engaging a friction roller 32 upon the armature shaft of a motor 33. A spool or reel 34 is rotatably mounted upon a stud 58 fixed to the shuttle to support a roll 35 of wrapping material, such as paper.

The invention particularly contemplates the provision of an improved mechanism of simple construction adapted to apply a substantially constant tension to the strip S of wrapping material as it is drawn from the roll. This device, as illustrated, is mounted upon the shuttle 16 and comprises a supporting plate 36 secured to the shuttle 16 by screws passing through the holes 37 and 38 in the plate. A lever 39 is pivotally mounted to engage the outer surface of the roll of wrapping material 35 and to turn freely upon a stud 40 upon the plate 36. In accordance with the preferred construction, the lever 39 is provided with a counterbalance arm 41 which is arranged to minimize the action of centrifugal force due to rotation of the shuttle. A brake member 43 is pivotally mounted at one end upon a stud 44 on the plate 36 and pivotally connected at its other end with a rod 45 by a pin 46. Preferably, the brake member 43 is positioned to extend radially of the shuttle. The rod 45 is provided with a reduced portion 48 for sliding engagement in a hole 49 in a lug 50 on the lever 39 on the side thereof engaging the roll. A spring 53 is positioned on the rod 45 so as to engage at one end a collar 54 loosely mounted upon the rod 45 and adapted to abut the lug 50. The other end of the spring 53 is held by and adjustably positioned relative to the rod 45 by nuts 55 engaging a threaded portion 56 on the rod 45 so that the compression of the spring may be adjusted to force the brake member 43 with a desired pressure against a drum 57 integral with or otherwise rigidly secured upon the spool 34 which grips the roll 35 of wrapping material. By such provisions the brake mechanism is arranged upon the shuttle so that the action of centrifugal force thereon will be exerted in a direction substantially tangential to the shaft upon which the roll of wrapping paper is mounted.

In operation the shuttle 16 and the work W are rotated at suitable desired relative rates by the driving mechanisms actuated by the motor 30, whereby the wrapping mate-

rial is drawn from the roll 35 and is caused to be wound spirally upon the work W. The desired braking action preventing the free rotation of the roll 35 is obtained by adjusting the compression of the spring 53 so it will force the brake member 43 against the drum 57 with the desired pressure. It will be noted that the braking action as effected by the spring 53 will vary depending upon the position of the lever 39 upon the outer surface of the roll 35, that is, as the diameter of the roll 35 becomes reduced in size, the lever 39 will move towards the center thereof thereby reducing the compression upon the spring 53 and the force which is exerted by the brake member 43. By providing the lever 38 with a counterbalance arm the action of centrifugal force thereon will be minimized by preventing change in its position tending to vary the action of the braking mechanism. So also it will be noted that by positioning the brake 43 so as to extend in a direction substantially radially relative to the shuttle the effect of the action of centrifugal force thereon will be reduced to a minimum.

What I claim is:

1. In a wrapping machine having means for supporting an article to be wrapped, the combination of a rotatably mounted spool for supporting a roll of wrapping material, a brake member pivotally mounted at one end and arranged to engage the spool, a lever pivotally arranged to engage the outer surface of the roll and having a projection on the side engaging said roll, a rod pivotally mounted at the other end of the brake member and slidably carried by said projection, and a spring surrounding said rod and engaging said projection to press said brake member against the spool.

2. In a wrapping machine having means for supporting an article to be wrapped, the combination of a shuttle rotatable around the article, a spool rotatably mounted on the shuttle for supporting a roll of wrapping material, and a brake mechanism mounted on the shuttle for engagement with said spool and arranged so that the action of centrifugal force has substantially no effect on the operation of the brake mechanism.

3. In a wrapping machine having means for supporting an article to be wrapped, the combination of a shuttle rotatable around the article, a spool rotatably mounted on the shuttle for supporting a roll of wrapping material, a brake mechanism mounted on the

shuttle for engagement with said spool and arranged so that the action of centrifugal force has substantially no effect on the operation of the brake mechanism, and means automatically controlling the braking action in response to variations in the diameter of the roll.

4. In a wrapping machine having means for supporting an article to be wrapped, the combination of a shuttle rotatable around the article, a spool rotatably mounted on the shuttle for supporting a roll of wrapping material, a brake member pivotally connected with the shuttle to extend in a direction substantially radial thereto and engage the spool whereby centrifugal force due to the rotation of the shuttle has substantially no effect on the operation of the brake member, a lever pivotally arranged to engage the outer surface of the roll, and means for controlling the action of the brake by the position of the lever.

5. In a wrapping machine having means for supporting an article to be wrapped, the combination of a shuttle rotatable around the article, a spool rotatably mounted on the shuttle for supporting a roll of wrapping material, a brake member pivotally connected with the shuttle to extend in a direction substantially radial thereto and engage the spool, a counterbalanced lever pivotally arranged on the shuttle to engage the outer surface of the roll, and means for controlling the action of the brake member by the position of the lever, the position of the brake member and the lever counterbalance being such that centrifugal force does not substantially affect the operation of the brake.

6. In a wrapping machine having means for supporting an article to be wrapped, the combination of a shuttle rotatable around the article, a spool rotatably mounted on the shuttle for supporting a roll of wrapping material, a brake member pivotally connected with the shuttle to extend in a direction substantially radial thereto and engage the spool, a counterbalanced lever pivotally arranged on the shuttle to engage the outer surface of the roll and minimize the effect of centrifugal force in the brake member, and a spring arranged between the brake member and the lever to exert a compressive action controlling the action of the brake member.

In testimony whereof I affix my signature.

JASPER DERRY.
